[57] ABSTRACT

An endless abrasive belt runs on a contact wheel and

on an idler wheel to perform grinding and sharpening operations on a rotary lawnmower blade. The cutting edges of such a blade are on the outermost ends thereof, and are each defined by the intersection of the flat face side of the blade and a surface ground away at an acute angle with the flat face of the blade. For each cutting edge, there is a taper back to the outer leading edge of the bar stock of which the blade is made. The grinding or sharpening is done in the usual manner for abrasive belt grinding wherein an endless coated abrasive belt is backed by a contact wheel having a cylindrical backup face, but the edge of the contact wheel adjacent the taper is relieved on a radius, and the endless belt extends out over this relieved radius and past the outer edge of the contact wheel. When the work is pushed against the abrasive belt and contact wheel, the grinding pressure exerted by the belt extending out over the radius and past the wheel varies from full pressure at the point where the relief starts, out to the outer edge of the belt where the only pressure is that occasioned by the centrifugal action of the abrasive belt itself. The result achieved is a smooth, even taper from the point of full contact with the wheel to a point where the abrasive belt is no longer in contact with the workpiece.

APPARATUS FOR SHARPENING BLADES

BACKGROUND OF THE INVENTION

Grinding or sharpening through the use of belt grinders whereby a contact wheel is powered to drive an endless abrasive belt which is riding over an idler pulley is well known in the art. Heretofore, however, it has been impossible to grind an elongated edge off of a flat longer edge of a workpiece while leaving the remainder of that edge of the workpiece unground. Heretofore such grinding has resulted in excessive wear and tearing of the abrasive belt at the edge of the contact wheel adjacent the point where the ground surface terminates. Even where the workpiece is provided with an initial taper between the end of the edge to be ground and the edge of the workpiece not to be ground, the abrasive belt will eventually, if not initially, snag and/or wear out along this outer edge portion long before the normal belt wear is achieved on the other portions of the belt.

Heretofore the suggested solution to this problem was to cut away or stamp out a circular area between the end of the elongated edge to be ground and that portion of the workpiece not to be ground or sharpened. This "solution" is not economically viable because it introduces a completely nonproductive extra step into the process of making products such as ordinary lawnmower blades where such edges are needed. This increases the price of production of such workpieces to the point where they are not economically saleable.

BRIEF SUMMARY OF THE INVENTION

An endless abrasive belt is assembled on a contact wheel and an idler wheel in the usual manner, but the edge of the contact wheel is relieved on a radius beginning at a point where the full grinding effect on the work is to terminate and where a taper from a ground surface to an unground surface is to begin. A belt is used which is wide enough to extend beyond the outermost relieved edge of the contact wheel.

A workpiece having a longitudinal edge on which a cutting edge is to be ground is held in any usual or preferred manner and is forced against the moving abrasive belt and against the contact wheel behind it. The desired surface will be ground in the usual manner, and also, a taper will be produced beginning from the point of full contact of the abrasive belt and contact wheel with the work to the point where the work is no longer in contact with the belt.

IN THE DRAWINGS

FIG. 1 is a side elevational view of a typical abrasive belt grinder set up to perform a grinding operation on a portion only of a longitudinally extending workpiece such as a rotary lawnmower blade, and showing the workpiece clamped in a fixture held in a pusher plate which is hydraulically actuated to push it against the abrasive belt and contact wheel;

FIG. 2 is a top plan view of the pressure assist grinding unit of FIG. 1 with a fragment of the contact wheel of the present invention shown in relation thereto, but with the pusher plate thereof backed off therefrom;

FIG. 3 is a perspective view of a rotary lawnmower blade workpiece showing in phantom the relation of a contact wheel and abrasive belt to it when grinding a cutting face and cutting edge in accordance with the invention;

FIG. 4 is an enlarged fragmentary sectional view taken on the line 4-4 in FIG. 1; and

FIG. 5 is a sectional view on line 5-5 in FIG. 4.

DESCRIPTION OF PREFERRED EMBODIMENT:

A rotary lawnmower blade workpiece 10 is designed to be supported through central holes 12 therein on a rotary lawnmower and to be rotated in direction to cause cutting edges 14 and 16 to cut grass as this mower is moved over the grass. Upswept ends 18 and 20 on either end of the blade serve as centrifugal fan blades drawing air and severed grass upwardly to be thrown from the mowing machine. Basically this blade 10 is made from flat, elongated bar stock and has a bottom blade face 26 and a parallel top blade face 28.

This invention deals with the efficient production of such blades, and specifically with the grinding away of parts of the edge of the bottom face 26 to form cutting faces 22 and 24 which intersect with top blade face 28 to form cutting edges 14 and 16, respectively.

The cutting faces 22 and 24 are produced by alternately clamping a first end 30 and then a second end 32 of the blade 10 in a hydraulically operated clamping fixture 34. This fixture includes a fixture block or pusher plate 66 which is sliddably mounted in a table block 36 on top of a table 38 and is propelled toward a contact wheel 40 by a table mounted linear hydraulic cylinder-piston motor 44 to force the blade 10 into the working surface of an endless abrasive belt 42.

The contact wheel 40 and endless abrasive belt 42 form a part of an abrasive belt grinder 46 which also includes a stand 48, electric motor 50, and means 52 to drive the contact wheel 40 from the motor 50 in a counterclockwise direction as seen in FIG. 1. Abrasive belt 42 is trained over idler pulley 54 which is rotatably mounted on stand 48.

Tie rods 56, 56 (one is shown) tie the table 38 to the stand 48 to withstand the pressure of the work against the contact wheel under the force of cylinder-piston motor 44.

OPERATION

A rotary lawnmower cutting blade workpiece 10 to be ground is placed in a bottom saddle 58 of the clamping fixture 34 with its first end 30 in contact with a stop plate 60. A linear hydraulic cylinder piston motor 62 is activated to carry an upper saddle 64 down against the blade 10 thus to positively fix its position during grinding with respect to the clamping fixture 34. This hydraulically operated clamping fixture 34 will be in the position as seen in dotted lines in FIG. 1 at the time the workpiece 10 is first clamped in it.

Once this clamping action has taken place, the linear cylinder-piston motor 44 is activated to push the fixture block 66, and consequently the entire fixture 34 forward to position as seen in full lines in FIG. 1. At that time, the lawnmower blade workpiece 10 and the contact wheel 40 as well as the endless abrasive belt 42 will be positioned with respect to each other as seen in FIGS. 3, 4 and 5.

As seen in phantom in FIG. 3, the portion or first strip of the abrasive belt 42 which is backed up by the contact wheel 40 will, under the force of the ram or linear motor 44, grind away a relatively straight, flat surface or cutting face 22 thus to form a straight sharpened cutting edge 14 along a portion only of the bottom longitudinal edge of the lawnmower blade 10. As best

seen in FIG. 4, at least one edge of the contact wheel, is relieved on a radius as indicated at 68. A second strip of the endless abrasive belt 42 extends beyond that edge of the contact wheel, and is, of course, not supported beyond the radius, except by its own stiffness and by the centrifugal force of its rapid movement with the contact wheel around the cylindrical path prescribed by that wheel. Thus, beyond the point of tangency of the relieved portion of the contact wheel and the cylindrical face of the wheel, the abrasive belt will have something less than its full force and effect on the work being ground. Farther along the abrasive belt toward the unsupported edge thereof, this force and effect becomes less and less, until the point is reached where there is no longer sufficient support to force the belt in against the workpiece. This results in a tapered 20 grind smoothly outwardly from the first strip backed up by the cylindrical face of the cutting wheel to the outer edge of the cut.

Extensive tests have now shown that there is no excessive wear on the unsupported part of the belt, nor is there any tendency for the abrasive belt to catch on the workpiece when its unsupported end extends clear out past the point of contact between the belt and the workpiece. Belts used in accordance with the present 25 invention have been found to wear out evenly over the entire area of contact with the cylindrical surface of the contact wheel; and do not have to be replaced any faster than belts used to grind materials which do not extend beyond the edges of the contact wheel.

Contrary to this, and before the present invention, this kind of sharpening was attempted with a structure substantially like that now indicated in FIG. 4 at the left end of the contact wheel. This structure tended to cut a shoulder sharply in against the portion of the workpiece which was not being sharpened and this shoulder eventually came to bear on the abrasive belt, causing 30 abnormal wear at the edge of the belt, and eventually tending to terminate the effective life of the belt long before the end of its normal working life over the cylindrical portion of the contact wheel.

While the invention has been described in connection with rotary lawnmower blades such as illustrated at 35 herein, it is to be understood that the invention is valuable wherever an abrasive belt grinder is to perform a grinding operation along a certain portion of a workpiece immediately adjacent to a portion of a workpiece which is to remain in the unground state.

The essence of the invention includes the use of an edge of the endless abrasive belt beyond a relieved 40

edge of a contact wheel to the point where the unsupported belt edge passes by the workpiece without coming in contact with it as the grinding progresses.

While the specification speaks of the contact wheel being relieved on a radius, it is to be understood that this relief could be at an angle, or could be tapered or rounded without involvement of a circle segment. It will be effective to go from full contact by the cylindrical portion of a contact wheel to a point where the only outward abrasive force of the abrasive belt is occasioned by the stiffness of the belt and the centrifugal action of it as it and the contact wheel move rapidly with respect to the workpiece.

The embodiments of the invention in which an exclusive property or privilege is claimed are defined as follows:

1. Apparatus for grinding a first section only of a work piece having at least first and second contiguous and continuous sections, said apparatus including:
  - a rotationally powered cylindrical contact wheel;
  - an idler pulley;
  - an endless abrasive belt having a first strip operatively mounted for grinding on the idler pulley and on a cylindrical portion of said wheel and having an integral second strip extending beyond an edge of the contact wheel;
  - said cylindrical portion of said contact wheel providing a continuous cylindrical support to the first strip of said endless abrasive belt, said first strip thereby being adapted to grind a straight surface of a first section of a work piece; and
  - means to hold said first section of said work piece against said abrasive belt to force said cylindrical support surface of said wheel against said first strip of said belt;
  - said second strip of said belt, when said first section of said work piece is so held, maintaining a position in spaced relation and out of contact with said wheel and being operative to abrade the work piece from the straight surface of its first section to a second section thereby to form in the work piece a taper from said straight surface to said second section.
2. The apparatus of claim 1 wherein said contact wheel is relieved along the edge thereof beyond which the belt extends to provide a relieved portion of progressively lesser diameter outwardly from said cylindrical surface.
